(57) **CLAIM**

The ornamental design for a chain, as shown and described.

DESCRIPTION

FIG. 1 is a perspective view of a chain showing the new design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is an enlarged top plan view thereof; and

FIG. 8 is an enlarged bottom plan view thereof.

FIG. 9 is an enlarged view of the encircled portion in FIG. 1.

FIG. 10 is an enlarged view of the encircled portion in FIG. 1.

FIG. 11 is an enlarged view of the encircled portion in FIG. 2; and,

FIG. 12 is an enlarged view of the encircled portion in FIG. 2.

The dash-dot lines in FIG. 1, FIG. 2, FIG. 9, FIG. 10, FIG. 11, and FIG. 12 illustrate the boundaries of the enlarged view indicators and form no part of the claimed design. The dash-dot-dot broken lines represent a break line, which depicts a symbolic break in the length of the chain. The appearance of any portion of the chain between the break lines forms no part of the claimed design. The dash-dash broken lines illustrate portions of the chain that form no part of the claimed design.
